(57) **CLAIM**

The ornamental design for a main unit for a surveillance camera, as shown and described.

DESCRIPTION

1. Main unit for a surveillance camera

1.1: Perspective

1.2: Top

1.3: Front

1.4: Left

1.5: Right

1.6: Rear view

1.7: Bottom

The dot-dash broken lines adjacent to the shaded areas

represent the bounds of the claimed design. Portions of the

(Continued)

main unit for a surveillance camera shown with broken lines
form no part of the claimed design.

1 Claim, 4 Drawing Sheets
